UNITED STATES PATENT OFFICE.

MARCEL LISSMAN, OF SACRAMENTO, CALIFORNIA.

TRACTOR.

1,323,704.

Specification of Letters Patent.

Patented Dec. 2, 1919.

Application filed November 6, 1918. Serial No. 262,264.

To all whom it may concern:

Be it known that I, MARCEL LISSMAN, a citizen of the Republic of France, residing at Sacramento, in the county of Sacramento and State of California, have invented a new and useful Improvement in Tractors, of which the following is a specification.

My invention relates to improvements in tractors and principally in the tractive treads thereof wherein a series of pivotally connected arcuate flights operate in conjunction with means for limiting the movement of said flights relatively to each other to form a rigid arcuate support for contact with the ground.

The primary object of my invention is to provide an improved tractor arranged to present an arcuate tractive area similar to that presented by a wheel of immense diameter by means of a comparatively small and compact device.

A further object of the invention is to provide an improved construction and arrangement whereby the tractor flights may be lubricated effectively to decrease frictional resistance.

I accomplish these and other objects by means of the device disclosed in the drawings forming a part of the present specification wherein like characters of reference are used to designate similar parts throughout the said specification and drawings, and in which—

Figure 1 is a view of my improved device partly in longitudinal section;

Fig. 2 is a transverse sectional view taken on line 2—2 of Fig. 1 in the direction indicated;

Fig. 3 is a plan view of Fig. 1 partly in section; and

Fig. 4 is an enlarged sectional view taken on line 4—4 of Fig. 1 in the direction indicated.

Referring to the drawings the numeral 1 is used to designate a pair of elliptical housings arranged parallel to each other and having centrally disposed elliptical slots 2 in the adjacent faces.

Pins 3 extend through the slots 2 and into the housings 1 so that opposite ends of said pins abut against the opposite inner faces of the housings 1 to take the lateral thrust of the tractive elements hereinafter more fully set forth.

The pins 3 are pivotally connected by means of links 4 and 6, said links 4 being

provided with sleeves 7 which are rotatably mounted upon the pins 3 and extend toward each other to the space between the housings 1.

Suitable anti-friction rollers 8 are rotatably mounted upon the sleeves 7 and traverse the interiors of the housing 1.

A slotted partition 9 is arranged within each housing 1 and in spaced relation to the inner faces or sides of said housings 1.

Within the space thus formed I have provided cheek-links which overlap at their adjoining ends and cover the slots 2 in the housings 1 to prevent the entrance of debris and the exodus of lubricating oil which is placed within the housings 1 to lubricate the several members therein and thereby decrease frictional resistance of said members.

The housings 1 are supported and rendered rigid by means of suitable castings or braces 12 which are in turn secured to a pair of central longitudinal channels 14 within which is rotatably mounted a driving shaft 16 carrying a suitable driving sprocket 86 wheel 17 having arcuate seats 18 arranged at regular intervals around the periphery thereof to engage and carry rollers 19 mounted approximately midway on the pins 3 in turn rotatably mounted within the housings 1.

A series of arcuate flights 20 are pivotally connected to each other by means of legs or extensions 21 which are alternately mounted upon the sleeves 7 and the pins 3 as disclosed in Figs. 1 and 4 of the drawings.

The flights 20 are each provided at their adjoining or abutting edges with inwardly extending flanges 22 which abut in certain positions to limit the movement of said flights, relatively to each other to form a rigid section comprising several members on the upper and lower portions of the consequent elliptical arrangement of the connected arcuate flights 20, the flights on the lower portion of said ellipse forming a support in the form of an arc of a circle of large diameter.

In this manner, by means of the rigid section of several flights 20, I have obtained the same tractive area as would be obtained with the use of wheel of a diameter that would render its use impracticable where a wheel of such size is used, thereby obtaining the same tractive advantages without the excessive weight.

Each of the flights 20 is provided on the

face thereof with treads 23 having serrated edges 24 which interlock when the flights 20 are in what may be termed an operative position and which separate a sufficient degree, when the flights 20 are slightly separated, as when turning the short ends of the elliptical formation, to prevent the entrance of large portions of earth or boulders which might tend to rupture the flights 10 when brought into an operative position.

It is obvious from the foregoing that I have provided an improved tractor having means for decreasing the frictional resistance as well as improved means for providing a rigid tractive section composed of several sections having means for limiting their movement relatively to each other to form such a rigid supporting section.

Having thus described my invention what 20 I claim as new and desire to secure by Letters Patent is—

1. A tractor comprising a pair of parallel elliptic housings having elliptical slots in their adjacent faces; a series of arcuate flights pivotally connected and having inwardly projecting flanges arranged to abut and limit the movement of the flights relatively to each other; pins connecting the flights and extending through the slots in the housings; links connecting the pins within the housings; means connected to and extending between the pins to close those portions of the elliptical slots between the pins to prevent the entrance of debris and 35 the exodus of lubricating material; and serrated overlapping plates secured to the outer surface of each flight.

2. A tractor comprising a pair of parallel elliptic housings having elliptical slots in 40 their adjacent faces; and a series of pivotally connected arcuate flights mounted for longitudinal movement within said slots and having means for limiting the movement of each flight relatively to each adjacent flight whereby a rigid section may be

formed of several adjoining flights to support the housings.

3. A tractor comprising a pair of parallel elliptic housings having elliptical slots in their adjacent faces; a series of pivotally connected arcuate flights mounted for longitudinal movement within said slots and having means for limiting the movement of each flight relatively to each adjacent flight whereby a rigid section may be formed of 55 several adjoining flights to support the housings; and serrated overlapping plates secured to the outer surface of each flight.

4. A tractor comprising a pair of parallel elliptic housings having elliptical slots 60 in their adjacent faces; a series of pivotally connected arcuate flights mounted for longitudinal movement within said slots and having means for limiting the movement of each flight relatively to each adjacent flight 65 whereby a rigid section may be formed of several adjoining flights to support the housings; and means for closing the elliptical slots between the flights to prevent the exodus of lubricating oil and the entrance 70 of debris.

5. A tractor comprising a pair of parallel elliptic housings having elliptical slots in their inner faces; a series of arcuate flights pivotally connected and having inwardly projecting flanges arranged to abut and limit the movement of the flights relatively to each other to form a rigid arcuate section comprising several adjacent flights to support the housings; pins connecting 80 the flights and extending through the slots in the housings; links connecting the pins within the housings; and a second set of links connected to and extending between the pins and arranged to cover the slots to 85 prevent the entrance of debris and the exodus of lubricating oil.

In witness whereof, I hereunto set my signature.

MARCEL LISSMAN.
